CLAIM

The ornamental design for a front control panel for a
combined vehicular cassette player and radio receiver,
as shown and described.

DESCRIPTION

FIG. 1 is a top, front and right side perspective view of
a front control panel for a combined vehicular cassette
player and radio receiver showing my new design;

FIG. 2 is a top plan view thereof;

FIG. 3 is a front elevational view thereof;

FIG. 4 is a bottom plan view thereof;

FIG. 5 is a left side elevational view thereof; and

FIG. 6 is a right side elevational view thereof.

FIG. 1.

FIG. 3.

FIG. 4.

FIG. 5.
